[57] CLAIM

The ornamental design for front control panel for a vehicular combined tape player and radio or the like, as shown and described.

DESCRIPTION

FIG. 1 is a front, top and right side perspective view of a front control panel for a vehicular combined tape player and radio or the like showing my new design; FIG. 2 is a top plan view thereof;

FIG. 3 is a front elevational view thereof;

FIG. 4 is a bottom plan view thereof;

FIG. 5 is a left side elevational view thereof; and

FIG. 6 is a right side elevational view thereof.

The broken lines in the drawing show environment only.

Fig. 1.Fig. 2.Fig. 3.Fig. 4.Fig. 5.Fig. 6.
